US00D878291S

(12) **United States Design Patent** (10) Patent No.: **US D878,291 S**
(45) Date of Patent: **** Mar. 17, 2020**

(54) **CHARGING DOCK**

(71) Applicant: **Bose Corporation**, Framingham, MA (US)

(72) Inventors: **Jason R. Pupecki**, Worcester, MA (US); **Jonathan Salerno**, Marlborough, MA (US); **Alexander Decastro Calachan**, Cambridge, MA (US); **Paul Summerson**, Berlin, MA (US); **Colin Taylor Mosgrove**, Needham, MA (US); **Emily L. Ballantyne**, Watertown, MA (US); **David Kaphammer**, Westborough, MA (US)

(73) Assignee: **Bose Corporation**, Framingham, MA (US)

(**) Term: **15 Years**

(21) Appl. No.: **29/674,512**

(22) Filed: **Dec. 21, 2018**

(51) LOC (12) Cl. **13-02**

CLAIM

The ornamental design for a charging dock, substantially as shown and described.

DESCRIPTION

FIG. 1 is a top, front, right side perspective view of a charging dock;

FIG. 2 is a back, bottom, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

(Continued)

The broken line portions of the drawings represent environmental structure only and form no part of the claimed design.

1 Claim, 8 Drawing Sheets
